UNITED STATES PATENT OFFICE.

WILLIAM GUSTAV LANGENHEIM, OF CHICAGO, ILLINOIS, ASSIGNOR, BY
DIRECT AND MESNE ASSIGNMENTS, TO ROBERT W. HUNT & CO., OF
CHICAGO, ILLINOIS, A FIRM.

CENTRIC-DRAFT UNDERFRAMING FOR CARS.

SPECIFICATION forming part of Letters Patent No. 716,063, dated December 16, 1902.

Application filed February 15, 1902. Serial No. 94,300. (No model.)

To all whom it may concern:

Be it known that I, WILLIAM GUSTAV LANGENHEIM, a citizen of the United States, residing at Chicago, Cook county, Illinois, have 5 invented certain new and useful Improvements in Centric-Draft Underframing for Cars, of which the following is a specification.

This invention relates to steel railroad-cars, and particularly to tank-cars, the primary 10 object of my invention being to provide a car of larger capacity than has been used heretofore and which shall be lighter than others in proportion to its load capacity.

A particular object of my invention is to 15 improve the underframing of steel cars, including the means of attaching the couplers.

Another object of my invention is to improve the construction of tank-cars and adapt 20 and provide an all-steel car for conveying liquids.

My invention consists generally in a car- 25 underframing comprising two longitudinal girders for the support of the load, said girders being connected by a plurality of transverse girders or saddles and having coupler attachments at their ends.

My invention further consists in a car-underframing comprising suitably-connected 30 longitudinal sills or girders in combination with a draft plate or girder provided at each end of the underframing and short sills extending therefrom adapted to hold the couplers, said plates transmitting the coupler stresses to the underframing.

My invention further consists in suitably-connected metal girders with horizontal draft- 35 plates secured to the bottoms of said girders and connecting the same, said plates carrying the truck-centers and serving as coupler attachments, and, further, my invention consists in various details of construction and in 40 combination of parts, all as hereinafter described, and particularly pointed out in the claims.

The invention will be more readily understood by reference to the accompanying drawings, in which—

Figure 1 is a side elevation of a tank-car embodying my invention, a portion thereof

being in vertical section. Fig. 2 is a plan 50 view of the underframing of the car, partly in horizontal section. Fig. 3 is an end view of the underframing. Fig. 4 is an isometric view of the underframing. Fig. 5 is an enlarged transverse section on the line $x-x$ of 55 Fig. 1. Fig. 6 is a detailed isometric view of the end of the underframing with the coupler attachment. Fig. 7 is a cross-section of a flat-car embodying my invention, and Fig. 8 is a modification of the construction shown 60 in Fig. 5.

My novel underframing is characterized and distinguished from cars of ordinary construction in two important particulars, to wit: first, the simplicity and light weight of 65 the underframing, the same being composed of but two girders instead of four sills, commonly employed, said girders being rigidly connected by parts extending between them and widely enough separated to safely carry 70 a load that is subjected to tilting forces, and, second, by draft attachments which occupy planes that include the axes of the couplers and are fastened under the end flanges of the girders, whereby the coupler stresses are 75 transmitted in a straight axial line from coupler to coupler, so that the underframing is relieved from detrimental vertical angular 80 stresses.

It is well known in engineering that the 80 strength of a steel structure depends largely upon the disposition or distribution of material and not wholly upon the mass or weight of same. I find that the quantity or weight of material required to support a given load 85 increases and decreases in proportion to the directness or concentric application of the load upon the material. This theory leads to the conclusion that a given load will be supported by a minimum quantity of steel in a 90 single girder connecting the truck-centers of a car; but inasmuch as the car is subjected to tilting forces it is necessary that the underframing shall be wide enough to allow for side bearings upon the trucks and sustain its 95 load on two distinct lines distant from the center line and between which lines the load, such as a tank, will be safely sustained and held

without need of uprights or side braces. That which is true regarding the support of the load by an assemblage of parts as closely as practicable to the center line is also true as to the weight and strength of material required to sustain the coupler shocks and stresses and transmit the same from end to end of the car.

My car in its preferred construction takes the form illustrated in the drawings.

Referring now to the drawings, it will be noted that the longitudinally-disposed material of the underframing is concentrated in two widely-separated girders 2 2 of the full length of the car and of a cross-section suitable to the maximum load to be carried. These girders are at once the draft-sills and the carrying-girders of the car and are rigidly connected at intervals by transverse girders 20 or saddles 3 3 and by the draft-plates 4 4, provided at opposite ends of the girders and whereon the girders may be said to rest. All parts are firmly riveted together, making an exceptionally rigid frame. The draft-plates 25 are applied to the under sides or flanges of the girders 2 2 and are riveted to the bottoms of the end saddles 3. Beneath the end saddles and on the insides of the draft-plates or horizontal girders 4 4 I provide the truck-centers 5. It will be noted that the plates 4 4 closely approach the truck-bolsters 6 and that the girders 2 2 preferably lie just within or just outside of the truck-wheels, only sufficient space being allowed for the swing of 30 the trucks. The girders are firmly tied together and stiffened by the transverse girders or saddles 3; but the frame is mainly dependent upon the large rectangular plates 4 for rigidity. The inner ends of the plates 4 40 are preferably stiffened by angles 8, as well as by the foot-flanges or angles of the end saddles or girders 3. The extreme ends of the girders are connected by the plates or angles 9 on the top thereof and by the plates 10 between the ends of the girders and somewhat below the lower flanges thereof. The height of the couplers above the rails is fixed by rule, and this construction of the underframing affords a draft-plate 4 at the exact required height, the same being in a place that includes the normal axes of the coupler. This being the case, it is possible to arrange the coupler frame or attachment above and below the plate 4, midway thereof.

55 The coupler attachment or frame comprises the four short angle bars or sills 11, oppositely arranged and having their inner ends riveted to the plates 4. The forward ends of the short draft-sills are connected by wide channel-60 plates 12 13, completing the frame for the coupler, and the forward ends are supported by the cross plate or channel 10.

14 14 are the stops for the coupler, which are embraced by the coupler-strap 15, which 65 incloses the buffer-springs 16. It will be noted particularly that the plates 4 include the projected axes of the couplers and that these

plates are practically continued in the under-flanges of the girders 2 and constitute a very light and strong connection from end to end 70 of the car, the coupler-strains being transmitted by the plates 4 to the girders, and vice versa.

When the underframing is for the support of the tank 16, the saddles 3 are provided 75 with concave upper flanges or surfaces 17, which conform to the bottom of the tank and which preferably rise slightly above the surfaces of the girders 2 (see Fig. 5) in order that the tank shall not rest upon the sharp edges 80 of the girders. The tank 16 is of sufficient width to rest firmly upon the frame; but I prefer to secure the same additionally by a number of strips 17, extending around the tank and attached to the bottoms of the girders 85 2. (See Fig. 5.) The tank 16 is nearly as long as the girders and after being placed thereon is blocked by the timbers 18 between the ends of the tank and the end plates 9 of the frame, these blocks taking the shock of 90 the tank, if any. If desired, lugs may be provided upon the tops of the girders and the bottom of the tank to prevent endwise movement of the tank. In a flat-car saddles with straight tops are used, same being then flush 95 with the tops of the girders 2 2. As shown in Fig. 7, nailing-strips 19 are secured on the girders 2, and the car-floor (not shown) is then nailed on the strips 19 and projects a considerable distance on each side of the girders 100 2. If desired, a low cross-saddle 3' may be provided above the coupler-space at each end of the frame, as shown in figure.

It is obvious that the advantages of the horizontal draft-plate 4—to wit, lightness and simplicity of construction and connection to the girders—may be secured in a vertical girder extending longitudinally of the frame and whereto the coupler-sills 11 would be similarly attached, with their stops occupying horizontal instead of vertical positions. It is also obvious that built-up girders and girders of different cross-sections may be employed in place of those illustrated, and it is further obvious that numerous modifications of my 115 invention will readily suggest themselves to one skilled in the art, and I do not confine my invention to the specific construction herein shown and described.

Having thus described my invention, I 120 claim as new and desire to secure by Letters Patent—

1. The centric-draft underframing for cars consisting of the two combined draft and carrying girders rigidly connected and having 125 upon their under sides draft-plates whereto the couplers are centrically attached, substantially as described.

2. The car-underframing consisting of two parallel vertical girders rigidly connected by 130 transverse saddles in combination with the centric-draft plates or girders whereon said vertical girders rest and are secured, substantially as described.

3. A car-underframing consisting of the two parallel girders rigidly connected by transverse saddles and having centric-draft plates or girders between their ends, in combination with short draft-sills extending from said draft-plates, substantially as described.

4. The car-underframing comprising the two longitudinal vertical girders, in combination with a plurality of transverse connecting girders arranged between the longitudinal girders and below the tops thereof and truck-centers and draft attachments at the ends of said longitudinal girders, the centers or axes of said attachments being substantially in the plane of the bottoms of said girders, substantially as described.

5. The car-underframing comprising the longitudinal girders connected by transverse girders, in combination with the draft-plates secured to the bottoms of the longitudinal girders, the truck-centers thereon and the coupler attachments extending from said plates, substantially as described.

6. The underframing for cars consisting of the two widely-separated girders joined by transverse saddles 3 and the truck-center plates whereon said girders rest, the short draft-sills extending from said plates, having suitable stops, and being concentric with said plates, substantially as described.

7. The coupler attachment comprising the horizontal plate or girder 4, in combination with the short auxiliary draft-sills extending therefrom and adapted to hold the coupler vertically midway of said plate and said plate being attached to the car-underframing, substantially as described.

8. The car-underframing comprising the parallel girders 2, the transverse girders 3 connecting the parallel girders 2 and the straight draft-plate 4 whereon said girders rest and are attached, in combination with the short draft-sills 11 having coupler-stops and attached to said plates 4, said girders 2 serving as both draft-sills and carrying-sills and the coupler loads and stresses being transferred thereto by said plates 4, substantially as described.

9. The coupler attachment comprising the horizontal draft plate or girder 4, in combination with the draft-sills 11 secured to the top and bottom of said plate 4 and holding the coupler with its axis in the plane of said plate 4, substantially as described.

10. The tank-car underframing comprising the two widely-separated vertical girders joined by a plurality of structural-shaped transverse girders, or saddles, the tank to the bottom of which said saddles conform and whereon the tank rests, the horizontal girders 4 and the coupler attachments secured thereto between the ends of the longitudinal girders, substantially as described.

11. The tank-car comprising the tank, the underframing of less width than the tank, but longer than the same and comprising the two girders 2 connected by tank-supporting saddles, the tank-blocks upon said girders, the

horizontal draft-plates secured to the bottoms of said girders and the centric-draft attachments secured to said plates between the ends 70 of the girders 2, substantially as described.

12. The combination with the coupler, of the draft-sills therefor and the draft-plate girder or web whereto said sills are attached and said plate occupying a plane that includes the projected axis of the coupler, substantially as described.

13. The underframing for cars consisting of the two combined draft and carrying I-beams or girders rigidly connected by transverse saddles and having upon their under sides and at their opposite ends draft-plates which serve as truck-center and coupler attachments, substantially as described.

14. The underframing for cars consisting of the two combined draft and carrying I-beams or girders, a plurality of transverse girders rigidly connecting the two I-beams and having flanged upper edges conforming to the arc of a circle, the tank-holding means arranged at the ends of said draft and carrying beams, the draft-plates secured to the under sides of said I-beams at the ends thereof and each also secured to one of said transverse girders and the coupler attachments secured 95 to said draft-plates between the ends of said draft and carrying beams, substantially as described.

15. The underframing for cars comprising the parallel girders having their lower flanges 100 in a horizontal plane, the horizontal draft-plates joining the lower flanges of said beams at the ends thereof, the truck-centers upon the under sides of said horizontal plates and the transverse saddles extending between 105 said beams and across said plates and secured to said beams and plates, substantially as described.

16. The underframing for cars comprising the parallel girders having their lower flanges 110 in a horizontal plane, the horizontal draft-plates joining the lower flanges of said beams at the ends thereof, the truck-centers upon the under sides of said horizontal plates, the transverse saddles extending between said 115 beams and across said plates and secured to said beams and plates and the coupler attachments each comprising a plurality of short draft-sills having their inner ends attached to said horizontal plates and having their outer 120 ends suitably supported between the ends of said girders, substantially as described.

17. The combination with the trucks of the horizontal draft-plates of greater width than said trucks, the truck-centers interposed between said trucks and draft-plates, the two draft and carrying sills arranged in parallel vertical planes and separated by a greater distance than the width of said trucks and a plurality of transverse beams or saddles extending from sill to sill and connecting said sills, substantially as described.

18. The combination with the trucks of the horizontal draft-plates of greater width than

- said trucks, the truck-centers interposed between said trucks and draft-plates, the two draft and carrying sills arranged in parallel vertical planes and separated by a greater distance than the width of said trucks and a plurality of transverse saddles extending from sill to sill and connecting the same, said saddles having convexed or recessed tops and the ends of said saddles rising above the tops of said sills, substantially as described.
19. The coupler attachments comprising the horizontal draft plate or girder 4 for attachment to the car-underframing and to rest upon a truck-center, in combination with four short draft-sills having their inner ends attached respectively to the upper and under sides of said plate 4, the vertical stops 14 connecting the upper and lower draft-sills in each

pair and horizontal connections between the outer ends of said sills, substantially as described. 20

20. The coupler attachment comprising the horizontal plate or girder secured to the underframing of a car, in combination with the sills secured respectively to the upper and under sides of said plate 4, the vertical stops 14 and the horizontal connectors 13, substantially as described. 25

In testimony whereof I have hereunto set my hand, in the presence of two witnesses, 30 this 1st day of February, 1902.

WILLIAM GUSTAV LANGENHEIM.

In presence of—

J. W. BECKSTROM,
H. G. BARRETT.
